UNITED STATES PATENT OFFICE

2,211,093

STATISTICAL CARD PUNCH

Karl J. Braun, Ridgewood, N. Y., assignor to
Remington Rand Inc., Buffalo, N. Y., a corporation of Delaware

Application May 5, 1937, Serial No. 140,833

49 Claims. (Cl. 164—114)

This invention relates to statistical card punching machines and particularly to reproducing card-punching machines wherein a series of pre-punched master-cards, having designation 5 punchings and data punchings therein, are used to control punch mechanism to transfer (selectively) the data punchings of the master-cards to a series of pre-punched detail cards which detail-cards are pre-punched with designation 10 punchings and which usually contain certain data punchings, although they always contain certain blank fields. These blank or unpunched fields are the ones to which the selected master-card data is transferred.

15 The present invention utilizes a standard Powers tabulator base, such as is shown and described in the Patent 2,044,119 to W. W. Lasker, as a general basic structure and the power drive and sensing heads of the present machine are almost 20 identical to the ones shown therein.

There are, generally, two ways in which the present machine may be used. It may be used as a plain reproducer or it may be used as a comparing reproducer. In using the machine as 25 a plain reproducer, a series of blank or unpunched detail-cards are punched with both designation and data punchings according to a series of pre-punched master-cards.

In using the present machine as a comparing 30 reproducer, a series of master-cards, which have been sorted sequentially according to designation punchings, are inserted into a master-card magazine. A series of detail cards, which also have been sorted sequentially according to their designation 35 punchings, are then inserted in a second magazine of the machine. A control dial (movable to two positions) is manually moved to a position which indicates that the machine will act as a "comparing reproducer," the motor 40 switch is turned on and the stop-start button is pressed in.

On the first operating cycle, the first detail-card will be fed into its sensing chamber and sensed but no master-card will be fed. On the 45 second cycle, the first detail-card will be retained in its sensing chamber and the first master-card will be fed into the master-card sensing chamber. At the end of this second operating cycle, the first master-card and first 50 detail-card will be sensed simultaneously and the designation punchings on both cards are compared through two removable translator units. If the designation punchings on both cards are found, by the machine, to be not identical, then the machine will retain the detail-

card in its sensing chamber and will, on subsequent cycles, feed only master-cards until a master-card is found that agrees in designatory punchings with the detail card. When this occurs all pins in the stationary master-card pin-box will be locked in their active positions and will condition the pins in the punch unit accordingly. On the next operating cycle, the master-card will be fed from its sensing chamber into a pocket on the rear of the machine; the detail-card will be fed into the punch chamber and punched with the data set up in the punch pins by the master-card; a new detail-card will be fed into its sensing chamber and sensed; and the master-card feeding means will then be disabled and no new master-card will be fed into the master sensing-chamber but the data set up by the master-card on the previous cycle will remain locked in the master sensing-head. It will thus be seen that, on subsequent operating 20 cycles, detail-cards (only) will be sensed and punched if they agree in designation punchings with the designation punchings locked in the master sensing-head. However, when a detail-card is sensed that does not agree in designation, 25 with the designation locked in the master sensing-head, then this detail-card will be retained in the detail sensing-chamber; the detail-card feeding-means will be disabled; the master-card sensing pins will be unlocked; and the machine 30 will continue to feed and sense master-cards until one is found that agrees with the retained detail-card as was previously explained. Thus, the machine, when conditioned by the manually operated dial as explained above, will compare the master-cards with the detail-cards and, when these comparisons agree (according to designatory punchings), the data in the master-card will be punched or reproduced in the detail-cards. The machine will continue to operate until the 35 master-card magazine is empty and it will then automatically stop. However, manually settable means are provided on both the master-card magazine and the detail-card magazine so that the machine can be made to stop, when either magazine has been emptied, or can be made to run continuously until the regular automatic stopping means on the detail-card sensing-chamber takes effect.

If it is desired to reproduce master-cards only, 50 then the dial (previously mentioned) is set in a position which indicates that the machine will be used as a plain reproducer. The pre-punched and pre-sorted master-cards are put into the master-card magazine and a number of blank 55

cards are inserted in the detail-card magazine and the machine is started. The machine will now feed one master-card and one blank card on each operating cycle and it will punch each 5 blank card with both the data and designation punchings held in the associated master-card. Thus the "comparison mechanism" is rendered ineffective and the entire punching (or any part thereof) in each master-card is reproduced upon 10 a respective blank card.

Manually operable means are provided for disabling various parts of the punch-setting mechanism so that any portion of the punchings of a given master-card may be reproduced in a blank 15 card or, if desired, all the punchings of the master-card can be reproduced.

One object of this invention is to duplicate any or all of the punchings of a pre-punched master-card upon a separate blank card.

20 Another object is to duplicate, from a pre-punched master-card, having "designation" punchings in one field and "data" punchings in one or more separate fields, the "data" punchings of the master-card upon a separate card 25 which has been pre-punched with "designation" punchings, identical to those in the master-card.

Another object of the present invention is to provide, in a statistical-card reproducing machine, means for mechanically comparing the 30 "designation" field of a pre-punched master-card with the pre-punched "designation" field of a separate card other than a master-card.

A feature of this invention is that it permits 35 the use of a series of removable translator units which are inserted in pairs so that different fields of a master-card or a detail-card may be used as "designation" fields.

Another feature is the provision of a manually 40 operable means which, at one setting, will cause the machine to compare the designation-field punchings of a set of master-cards with the designation-field punchings in another set of cards as well as to punch data punchings, in this other set of cards under control of the master-cards and which, at another setting, will cause 45 the machine to reproduce any or all of the punchings of a set of pre-punched master-cards upon a separate set of blank cards.

A third feature of the present invention is a 50 novel card feeding and stopping mechanism whereby, when a detail-card does not agree in designation punchings with a master-card, the detail-card is held in its sensing-chamber while only master-cards are fed and whereby, when a 55 master-card agrees with a detail-card, the master-card designation is locked in its master-card sensing-head and only detail-cards are fed.

Still another feature of this invention is the 60 provision of manually settable means, associated with both master-card and detail-card magazines, whereby the machine will stop when either, or both, of the magazines are empty or whereby the machine may be made to run, after 65 either or both of the magazines are empty.

Other objects, features, and structural details of the invention will be apparent from the following description when read in connection with the accompanying drawings, in which:

70 Fig. 1 is an isometric drawing of the machine with all covers in place;

Fig. 2 is a rear elevational view of the machine with the covers in place;

Figs. 3, 4, and 5 together form a sectional elevation, as seen from the left-hand side, taken

just inside the left-hand main frames of the machine;

Figs. 6, 7, and 8 together form a sectional elevation, as seen from the left-hand side, taken substantially through the middle of the machine; 5

Figs. 9, 10, and 11 together form an elevation of the machine, as seen from the left-hand side, with the cover plates removed;

Figs. 12, 13, and 14 together form an elevation of the machine, as seen from the right-hand 10 side, with the cover plates removed to show the power drive gearing.

Figs. 15, 16, and 17 together form a front elevation of the machine with the cover plates removed; 15

Figs. 18, 19, and 20 together form a rear elevation of the machine with the cover plates removed;

Figs. 21 and 21A together form a top plan view of the machine with the cover plates removed; 20

Fig. 22 is a left-side elevational detail of the stopping and starting mechanism for the machine;

Fig. 23 is a top plan view of the automatic stopping mechanism; 25

Fig. 24 is a left-side elevational detail view of the card feeding mechanism for the machine, and it includes the "retract" mechanism for the master-card sensing-head;

Figs. 25, 26, and 27 are left-side sectional elevational details of the card feeding mechanism for the machine; 30

Fig. 28 is a fragmentary top plan view of the card feeding mechanism;

Fig. 28A is an enlargement of Fig. 28. 35

Fig. 28B is an isometric detail of the card-feed latches.

Figs. 29 and 30 are left-side sectional elevational detail views of the card-stop mechanism;

Fig. 31 is a top plan view of the "control unit" 40 for the machine.

Fig. 32 is a fragmentary rear elevation of the "control unit" operating mechanism;

Figs. 33, 34, and 35 are left-side elevational detail views of the mechanism contained in Fig. 32. 45

Figs. 36 to 42 are diagrams showing the arrangement of the plates of drawing in composite views.

Machine frames 50

As will be seen from Figs. 1 and 2, the base castings of the present machine are similar to the castings of a regular Powers tabulator. A square casting 1 has fastened thereto, four legs 2 and supports a frame casting 3 upon its top edge. 55 Fastened to the left-hand side of the frame 3, is a box-like casting 4 which has a removable cover plate 5. An identical box-like casting 6 is secured to the frame 3, upon its right-hand side, and has a cover plate 7 which is identical with the left-hand cover plate 5. Securely fastened to the top of the left-hand casting 4, is a box-like casting 8 which has a cover plate 9. A dial 10 protrudes through the casting 8 and this dial 60 is manually settable to two positions which will be described in detail later on. Securely fastened to the top of the right-hand casting 6, is a box-like casting 11 which is similar to the casting 8 and this casting has a cover plate 12 which is like the cover 9. A single-piece front cover plate 13 runs from the frame casting 3 to the middle of the upper or master-card magazine as shown and a top cover plate 14 rests upon the front cover plate 13 and upon the top sides of the castings 8 and 11. In the rear of the machine, 65

a door 15 is hinged to the casting 8 and it will be seen that this door is formed with a pocket 16 to receive the master-cards when they are ejected. A rear cover piece 17 is formed with a pocket 18 for the reception of the detail-cards after they have been punched according to the master-cards.

As seen in Figs. 15, 18 and 19, a plurality of bars such as the bars 19 run front to rear in the machine and are securely fastened to the side castings. Fastened to these bars 19 (Figs. 15, 16, 18 and 19) are a number of cross bars 20 and upon the bars 19 and 20 are fastened all the assemblies which lie between the inner walls of the side castings with the exception of the detail-card pin box and the punch mechanism. These are supported by the castings 3, 4, and 6. The detail-card pin box is mounted in the same fashion as that set forth in the Patent 2,044,119 to W. W. Lasker.

Power drive

As seen in Fig. 14, a belt 24, which is driven by a continuously running motor 25 (see Figs. 2 and 17), turns a pulley 26. The pulley 26 is loosely mounted upon a shaft 27 which carries a spring-pressed friction clutch member 28. The clutch member 28 is operated through an arm 29 (fast on a cross-shaft 29A) by the usual toggle stop-start mechanism, shown in Fig. 11, which is old and well known in the art.

The shaft 27 (Fig. 14) carries a number of worm screws of which the worm 30 drives a gear 31; the worm 32 drives a gear 33; the worm 34 drives a gear 35; the worm 36 drives two gears 37; and the worm 38 drives two gears 39. The gears 31, 33, and 35 are fast respectively upon the right-hand ends of shafts 40, 41, and 42. The shafts 40, 41, and 42 carry feed rolls and extend laterally across the machine and are geared (as shown in Fig. 11) to worms held upon a shaft 43 supported by the left-hand casting 4. The power-driven feed roll or conveyor system in the present machine is almost identical to that shown in the Patent 2,044,119 and it is not claimed as new herein. Referring to Figs. 12, 13, and 14, the shaft 27 (Fig. 14) carries, near its rear end, a beveled gear 44 which constantly meshes with a gear 45, fast upon the lower end of a shaft 46. The upper end of shaft 46 carries a similar beveled gear 47 (Fig. 12) which meshes with a gear 48 to turn the shaft 49. The shaft 49 drives two sets of feed rolls through the shafts 50 and 51 in the usual manner.

As seen in Figs. 11 and 14, a shaft 52 runs laterally across the machine and is positively driven by a gear on its right-hand end which meshes with the worm 36. This gear is not shown in the drawings of the present invention because it is herein covered by a dial 53. However the gear is the same as a gear 54 (Fig. 14) which meshes with and is driven by the worm 38. Dial 53 is for the purpose of adjusting the timing of the machine and forms no part of the present invention. The gear 54 is fast upon the right-hand end of a shaft 55 which extends laterally across the machine and holds upon its left-hand end, two cams 56 and 57 (Fig. 11). The shaft 52 and the shaft 55 are journaled in the inner walls of the frame castings 4 and 6. Shaft 52 is the main operating shaft of the machine and shaft 55 is the secondary operating shaft.

Stop-start mechanism

The present machine can be started or stopped

by the regular stop-start button 60, shown in Fig. 11, in the same way that the regular Powers tabulator is started and stopped. The usual mechanism for stopping the machine when no card is sensed, is not illustrated in the present drawings, but is designated generally by the reference characters 275-276 in Fig. 26 of the Lasker patent. In the present machine, this mechanism is used on the detail-card sensing-head only. As is seen in Figs. 3 and 15, the master-card magazine (which is the upper magazine) consists generally of two side walls 61 which are suitably fastened to a bottom plate 62. The plate 62 is fastened to supporting brackets 63 by bolts 64. The supporting brackets 63 are suitably fastened to the castings 8 and 11. In the present embodiment, they are fastened by bolts 65 (see Fig. 3). The lower or detail-card magazine (Fig. 4) is of identical construction and is supported between the frame castings 4 and 6. Referring to Figs. 3, 4, 22, and 23, it will be seen that each magazine is equipped with a manually operable stop-latch. The upper latch 66 is loosely pivoted upon a stud 67 which extends toward the right-hand side of the machine and is held by a supporting bracket 68 fastened to the bottom plate 62 of the master-card magazine. The latch 66 is pressed toward the front of the machine by a spring 69, anchored, at its rear end, to the tail of the latch 66, and, at its front end to a stud 70 held on the bracket 68. The bracket 68 is formed with a slot through which the latch 66 passes. The latch 66 is formed with a shoulder 71 for engagement with the slot in bracket 68 and is further formed with a slot 67A, as shown in Fig. 22, and it will thus be evident that, when the latch 66 is depressed, the shoulder 71 will ride under the forward edge of the slot in the bracket 68 and will then, under tension of spring 69, remain latched down until it is manually released. Loosely mounted upon the stud 67, is a lever 72 which has a downwardly extending tail the same as the latch 66. Anchored between this tail, on the lever 72, and the stud 70, on bracket 68, is a spring 73 (Fig. 23) which tends constantly to draw the lever 72 counter-clockwise as seen in Fig. 22. The lever 72 extends forward (toward the front of the machine) far enough so that it lies under a pin 74 which is held by the latch 66 and extends rightwardly therefrom. The lever 72 carries a pin 75 which extends rightwardly through a slot 76 in an upright link 77. Between the link 77 and the lever 72 is an upright finger 78 which passes through a hole in plate 68 and is adapted to cooperate with a hole 79 in a card-weight 80. The lower end of link 77 is pivotally attached to the rearwardly extending end of a rock-lever 81 rigidly secured to the right-hand end of a shaft 82. Upon the left-hand end of shaft 82 is the usual lever 83 which pivotally supports an interponent 84 which cooperates with the usual push-link 84A (see Fig. 22) by which the machine can be stopped as is old and well-known. From the foregoing it is evident that, when the latch 66 is moved from its Fig. 22 position to its Fig. 3 position, the pin 74 thereon will move the lever 72 to a position where its pin 75 will be resting in the bottom of the slot 76 and it will be further seen that, with the pin 75 in this position, the link 77 will be held in its down position and the machine will continue to operate regardless of whether or not there are any cards in the master-card magazine. It is also seen that, if the latch 66 is in its non-depressed position (shown in Fig. 22), then the 75

machine will operate until the last card passes out of the master-card magazine. As soon as the magazine empties, spring 73, on lever 72, swings the lever 72 counter-clockwise (Fig. 22) 5 and raises the link 77. This rocks the lever 81 and shaft 82 to shift the interponent 84 to its rearward, or active, position and thus stop the machine.

A similar arrangement is shown in Fig. 22 for 10 the detail-card magazine and here a similar latch 85 acts upon a spring-pressed lever 86 to raise a link 87. The link 87 is slotted at its upper end and is pivotally connected to the lever 81 by a stud 88 and a spring 89. Thus, it is seen that the 15 machine can be stopped automatically by first setting the latches 86 and 85 on the card magazines. This is a necessary function of the present invention as it sometimes occurs that the detail-card magazine runs empty before the master-card magazine. If there were no mechanism for 20 automatically stopping the machine at such a point, one of the remaining master-cards would be fed out of the machine and would have to be reinserted.

25

Control unit

The card-stop mechanism, the card feed mechanism, and the retract mechanism, for the master-card sensing-head and the detail-card 30 sensing-head, are all controlled by a single, ratchet-operated, control unit which is shown in plan in Fig. 31 and in elevation in Fig. 11. As seen in these two figures, the control unit is fixed to the top of the left-hand frame casting 4 by 35 means of two screws 90 which pass through a small casting 91. The casting 91 (or control unit casting) carries, near its center, two ball bearings (not shown). Mounted for rotation in the ball bearings is a cam shaft 92. The shaft 92 holds, 40 fast upon its left-hand side, a detent cam 93, a ratchet disk 94, and an identical ratchet disk 95. The ratchet disks are spaced apart by a collar 96 and are operated by mechanism which is most clearly shown in Figs. 11, 31, 32, 33, 34, 45 and 35.

From these figures, it is seen a bell crank 97 is 50 pivotally mounted upon a stub shaft 98 held stationary upon the left-hand side of the control unit casting 91. The bell crank 97 has a rearwardly extending arm 99 which carries a leftwardly bent off ear 99A. Near its middle, the arm 99 pivotally supports the lower end of a link 100. The upper end of the link 100 is pivotally supported by the rear end of a rock- 55 arm 101, the forward end of which is securely fastened to the extreme left-hand end of a shaft 102. The shaft 102 (most clearly shown in Figs. 15 and 16) extends laterally across the front of the machine and is journaled in the inner walls of 60 the castings 8 and 11. Fast upon the shaft 102 is a pair of bail arms 103 which support, between their upper ends, a bail rod 104. This bail rod 104 is constantly urged counter-clockwise, as seen in Fig. 33, by a spring 105 anchored, at 65 its upper end, to the arm 101 and, at its lower end, to a stud carried upon the frame casting 8. Referring for a moment to Figs. 6 and 7, it will be seen that the bail bar 104 normally rests against the forward edges of a set of manually 70 operable interponent members 106. A plurality of comparison slides 107 (Fig. 6), which are made in two parts with small bent-off lugs 108 thereon for the sake of convenience in assembly, are mounted between cross-bars 20 and are 75 guided thereby. At certain times, (to be fully

described in connection with sensing), one or more of the comparison slides 107 are moved toward the front of the machine. It will thus be seen that if, at the time the slides 107 move forward, an interponent or interponents 106 are in their upper or active positions, (see Figs. 33 and 34) then the slide or slides 107 will rock the bail bar 104 clockwise with its pivot shaft 102. It will further be seen that the clockwise rocking of the shaft 102 will pull up on the link 100 (Figs. 10, 11, 32, 33, 34, and 35) and that this will rock the bell crank 97 clockwise to the position shown in Fig. 35 where it will remain until the comparison slides 107 are allowed to return to their rearward positions. When the slides 107 are in 15 their rearward positions, the ear 99A of the bell crank 97 is free to follow the movements of a push-link-operated rock-arm 110 as is best shown in Fig. 34. The rock-arm 110 is pivoted upon the left-hand end of a stud 111 which is held on 20 the left-hand face of the control unit casting 91. A spring 112 is anchored, at its forward end, to a stud 113 (extending rightwardly from rock-arm 110) and, at its rearward end to a stud 114 which is held fast in the left-hand face of the 25 casting 91. This spring 112 keeps the rock-arm 110 in constant contact with the top of a push link 115 which link is guided, for vertical sliding movement, at its upper end, in a slot in the casting 4. At its lower end, the push link 115 is 30 pivotally supported by a rock-arm 116 which is pivoted, at its rear end, upon a stud 117 held in the frame casting 4. The rock-arm 116 carries, (near its forward end) an anti-friction roller 118 which follows the periphery of a cam 119, which 35 cam is keyed to the main operating shaft 52 and stands in its normal, unoperated position, in Fig. 34. It is thus seen that, as the main shaft 52 turns, the link 115 will cause the rock-arm 110 to move down and up and it will be particularly 40 noted that the upward movement of the rock-arm 110 will be very fast and will occur at the very beginning of every cycle of the machine.

A ratchet-operating pawl 120 is pivotally mounted upon the left-hand side of the rock- 45 arm 110 by a rivet or stud 121 which extends through the rock-arm 110 and also forms a pivot for a ratchet-operating pawl 122, held upon the right-hand side of the rock-arm. Two springs 123 tend, constantly, to draw the pawls 120 and 50 122 into engagement with the ratchet disks 94 and 95 respectively. However, as only one pawl at a time is allowed to come into active engagement with the ratchets, a means is provided for blocking the action of one pawl while the other 55 is turning its ratchet disk.

As is best shown by Figs. 33, 34, and 35, the bell crank 97 has a downwardly extending arm 125 which carries, at its lower end, a rightwardly extending pin 126. The pin 126 extends into a 60 slot 127 in a slide 128. The slide 128 is mounted, for forward and rearward sliding movement, upon the stud 111 and the stud 114. Slide 128 holds, upon its left-hand side, a long pin 129 which extends under both the pawl 122 and the pawl 65 120. It is thus seen that, if the slide 128 is in its forward or Fig. 34 position, the pin 129, thereon, will hold the pawl 122 out of active engagement with its ratchet disk 95 and allow the left-hand pawl 120 to actively engage its ratchet 70 disk 94. It will also be seen that, if the slide 128 is in its rearward or Fig. 35 position, the pin 129 will permit the pawl 122 to engage its ratchet disk 95 and will withhold the pawl 120 from active engagement with the ratchet disk 94.

As seen in Figs. 4 and 31, there are, fixed upon the right-hand end of shaft 92, three cams, each having four high points and four low points. All three cams are identical in size and shape. The cam 130 controls the card-stop mechanisms for the two sensing heads; the cam 131 (Fig. 24) controls the retract mechanisms for the master-card pin box; and the cam 132 controls the card feeds for both sensing heads. The cams 130, 131, and 132 are fixed to the shaft 92 in such a manner that their outlines appear, when viewed from the left-hand side of the machine, as shown in Fig. 4. In Fig. 4 the outlines of cams 131 and 132 are coincidental while the outline of cam 130 shows a variation of one-eighth of a revolution or forty-five degrees. The control shaft 92 is held in its various positions by a detent arm 133 (see particularly Figs. 31 and 11) which is loosely mounted upon the shaft 98; the detent arm 133 carrying an anti-friction roller 134 for engagement with the detent cam 93. A spring 135 anchored at its upper end to the detent arm 133, and at its lower end to a spring retainer (mounted on stud 111), keeps the roller 134 constantly against the cam 93.

Card feed mechanism

As seen in Figs. 6, 7, 15, 16, and 17, the master-cards and detail-cards are fed by standard picker-knives such as are used in all Powers tabulators and shown in Patent 2,044,119. The master-card picker-blade 140 is operated by the usual picker link 141 and lever 142. Lever 142 is securely fastened to a shaft 143 which runs laterally across the front of the machine and is journaled in the side frame castings 8 and 11. The detail-card picker blade 144 is operated by a similar link 145 and lever 146. The lever 146 is securely fastened upon the middle of a shaft 147 which is journaled in the side castings 4 and 6. As is best shown in Figs. 10, 11, and 24, the cross-shaft 143 has securely fastened to its extreme left-hand end, a short crank-arm 148 which pivotally supports the upper end of a long link 149. The lower end of the link 149 is pivotally connected at 150 to a short crank-arm 151. The crank-arm 151 is fastened to a hub 152 which hub is fast on an upright arm 153. The hub 152 is loosely mounted upon the shaft 147. Referring to Figs. 24 to 28 inclusive, it is seen that an upright arm 154 (Fig. 28A), identical in size and shape to the arm 153, is securely fastened to the shaft 147. Arms 153 and 154 carry, at their upper ends, pins 155 and these pins are constantly held against shoulders 156 on slides 157 by a pair of very strong springs 158; anchored, at their forward ends, to studs 159 carried by the arms 153 and 154 and at their rear ends to a stud 160 carried by the inner wall of the frame casting 4. The slides 157 are mounted for forward and rearward sliding movement upon a pair of studs 161 and are held against lateral movement by collars as shown in Fig. 28. The rearmost edges 162, of slides 157, are, thus, held in contact with a pair of anti-friction rollers 163 which are carried on the upper ends of a pair of equal and similar arms 164. The arms are formed integral with a hub 165 so that the hub 165 and the arms 164 turn or oscillate together as one piece. Hub 165 is loosely mounted upon a stud 166 which projects leftwardly from the frame 4 and the hub is properly positioned and held upon the stud 166 by a pair of screw-collars 167. A picker cam 168 is fast upon the main operating shaft 52 and upon the periphery

of this cam 168 rides a follower roller 169 which is fastened on the left-hand arm 164. From the foregoing description, it will be understood that, unless one of the slides 157 is held in its forward or Fig. 24 position, both slides will follow the oscillatory movement imparted by the picker cam 168 and both picker knives will feed cards simultaneously. However, it is sometimes desired to feed cards from either the master-card magazine or the detail-card magazine without feeding from the other. For this purpose, the following mechanism is supplied and it will hold either one picker or the other inactive by holding one or the other of the slides 157 in the Fig. 24 position.

Referring to Figs. 24 to 28A inclusive, and Fig. 31, a long upright link 170 stands in normal position in Figs. 24 and 26 and is pivotally supported, at its bottom, by a rearwardly extending arm 171 (see particularly Figs. 28 and 28A). The top of the link 170 carries a pin 172 which rides in a slot 173 in the lower end of a short link 174. Near the top of the link 170 is a slot 175 and in this slot 175 rides a rightwardly extending pin 176 held by the forward end of a lever 177. The lever 177, as is most clearly seen in Fig. 31, is loosely mounted upon the right-hand face of the control unit casting 91 and is held in place by, and pivoted upon, a screw 178. Lever 177 is tensioned counter-clockwise as seen in Figs. 24 to 27 inclusive, by a spring 180 anchored at its lower end to a stud 181, carried by the left-hand frame casting 4, and anchored at its upper end to a stud 182, carried upon the left-hand side of the lever 177. Carried upon the rearward end of the lever 177, is an anti-friction follower roller 183 which is guided by the card feed cam 132 (previously mentioned). When in its normal position, shown in Figs. 24, 26, and 31, the roller 183 rests upon one of the high parts of the card-feed cam 132 and the pin 176, in the forward end of the arm 177, rests in the top of the slot 175 in the link 170. A spring 184, anchored at its lower end to the pin 176 and at its upper end to the pin 172, tends constantly to keep the pin 176 in the upper end of the slot 175. Another spring 185 is anchored, at its lower end, to a stud on the link 174 and, at its upper end, to a pin 186 carried by the rearwardly extending arm 187 of a bell crank which has a downwardly extending arm 188. The spring 185 is stronger than the spring 184.

The previously mentioned arm 171 is fast upon the right-hand end of a short shaft 189 which is journaled in the frame casting 4. The shaft 189 carries, upon its left-hand end, a hook 190 and an adjacent hook 191 (see Figs. 28A and 28B), each hook carrying a pin 192. The hooks are pressed together, by a spring 193, so that their edges contact the pins 192, which pins limit the hooks in such a manner that there is always a definite space between their noses. The hook 190 is fastened to the shaft 189 by a screw collar or any other suitable means but the hook 191 is loose. A pin 194 extends from each slide 157 toward the other, as is most clearly shown in Fig. 28A, and these pins 194 cooperate with the hooks 190 and 191 to latch or lock out one or the other of the slides 157 and hence one or the other of the pickers. In the normal position of the machine (see Figs. 24 and 26) with the card feed control cam 132 in the position shown, the lever 177 is (through spring 184) holding the link 170 in its lowest position so that the arm 171 has swung counter-clockwise and positioned the hook 190 over its associated pin 194. This position posi-

tively keeps the left-hand slide 157 from following its roller 163 and it is, thus, evident that the lever 153 is held inactive against the tension of its spring 158. This disables the upper or master-card picker and the machine will feed only detail-cards until the card-feed control cam 132 is turned one-eighth of a revolution. In this position, best illustrated by Fig. 25, the lever 177 has positively pulled the link 170 to its uppermost 10 position and the hook 191 is now engaging the pin 194 on the right-hand slide 157. This disables the lower or detail-card picker but allows the master-card picker to feed. There is a neutral or intermediate position of the hooks 190 and 15 191, which is illustrated in Fig. 27, but this will not be described at present because this position is not under the control of cam 132 but is gained from the aforementioned dial 10.

Retract mechanism

20 In the present machine, the detail-card stationary pin-box has no retract slides or mechanism but the stationary pin-box for the master-card sensing head, at certain times retains a 25 single pin-set-up for a number of machine cycles. It is, therefore, necessary to have the usual retract slides and release ball for this sensing head. Referring to Figs. 11, 24 and 31, it is seen that a cam 197 (Figs. 11 and 24), fast upon the main 30 operating shaft 52, has a lug 198 upon its periphery and that the cam 197 acts upon a follower roller 199, held on a rock-arm 200, which is pivoted at 201 to the frame casting 4. The rock-arm 200 pivotally supports the lower end of a push link 35 202, the upper end of which is guided by a slot in the top wall of the casting 4. A forwardly extending rock-arm 203, fast on the left-hand end of a rock-shaft 204, lies in the same vertical plane as the link 202 and is adapted to be engaged thereby. Shaft 204, as can best be seen in 40 Fig. 31, runs laterally in the machine and terminates just beyond the inner wall of the frame casting 4. The shaft is suitably supported by a bracket 205, at its left-hand end, which is bolted 45 to the frame 4; and by a bracket 206, at its right-hand end, which is fastened to the cross bars of the stationary detail-card pin box D. Referring to Figs. 3, 4, 5, 24, and 31, a lever 207, having a forwardly extending arm 208, is loosely mounted 50 upon the shaft 204 and is prevented from moving laterally on said shaft, by a screw collar 209 (Fig. 31). The arm 208 carries, upon its right-hand face, an anti-friction roller 210 which is adapted to follow the periphery of the retract cam 131 and which, in its normal position (Figs. 4, 24, and 31), 55 lies upon one of the low parts of the cam. The lever 207 pivotally supports, at its top, the front end of a rearwardly extending link 211. The link 211 is made with a slot 212 through which passes 60 a pin 213, carried by a lever 214, pivoted at 215 on a long link 216. A spring 217 tends constantly to hold the pin 213, on lever 214, in the rear end of the slot 212. Pivoted adjacent the link 211, on the lever 207, is a forwardly extending link 65 218, having a slot 219 in its forward end. A pin 220, held by the depending arm 188, passes through the slot 219 and thus supports the forward end of the link 218.

Pinned to the rock-shaft 204, there is a pair of 70 rearwardly extending arms 221 which carry, between their rear ends, a pin 222. The pin 222 rides in a slot in the lower end of the link 216.

From the foregoing, it will be seen that, if the 75 retract-cam 131 is in its normal position while the main shaft 52 is revolving, the cam 197 will

cause the link 202 to move up and down and rock shaft 204 counter-clockwise and then clockwise for every revolution of shaft 52. The rocking of shaft 204 will cause pin 222 to ride idly down and up in the slot in link 216. However, when the retract-cam 131 is turned one-eighth of a revolution, so that the roller 210 rests upon one of the high parts, then the link 211 will be moved toward the rear of the machine and will carry, with it, the pin 213. This will move the hook 214 A 10 under the pin 222 and, as the pin 222 moves up and down, the link 216 will be moved to operate the retract ball for the master-card sensing-head. The top of the link 216 is pivotally supported by one end of a U-shaped link 223. The other end of the link 223 is securely fastened to the left-hand end of a rock-shaft 224. The rock-shaft 224, as is well shown in Fig. 18, extends laterally across the rear of the stationary master pin box and is supported at each end by angle brackets 20 225 screwed to the rear support bars of the stationary master pin box. Referring to Fig. 6, it is seen that the usual retract arrangement prevails, i. e., locking slides 226 are normally drawn toward the rear of the machine by leaf springs 25 227. A bail-bar 228 is supported between a pair of bail arms 229 (see also Fig. 18) and is operated, as has just been described.

Card stop mechanism

20

Figs. 3, 4, 5, 11, 18, 29, 30, and 31, show the card-stop mechanism, in its entirety, for the master-card sensing chamber and for the detail-card chamber. Referring to Figs. 11, 29, 30 and 31, mounted upon the main operating shaft 52, is a card-stop operating-cam 230 (see Fig. 29) (which is the regular card-stop cam for the Powers tabulator). A rock-arm 231, is pivoted upon a stud 232, held by the frame casting 4. The rock-arm 40 231 pivotally supports, at its forward end, the lower end of a push-link 233. A follower roller 234, fast upon the right-hand side of arm 231, rides on the periphery of the cam 230. The upper end of the link 233 is pivotally attached to the 45 forwardly extending end of a rock-arm 235, the rear end of which is pinned (by a hub) to a rock-shaft 236. The rock-shaft 236 is journaled in the angle-brackets 205 and 206, already mentioned in regard to the retract mechanism. 50 Pinned to the right-hand end of the shaft 236, by a hub 237, is a forwardly extending arm 238. The forward end of the arm 238 pivotally supports the lower end of a long link 239 pivoted, at its upper end, to a rock-arm 240. The lever 55 238 has a rearwardly extending nose 241, which nose, underlies a pin 242 on a rock-lever 243. The lever 243 is loosely mounted upon the shaft 236 but is made fast to the right-hand face of a hub 244 as is best seen in Fig. 31. The hub 244 is 60 made fast, on its left-hand side, to a forwardly extending lever 245 and it will, therefore, be seen that the hub 244, the lever 243, and the lever 245 are all loose upon shaft 236 and that the two levers and their hub turn together as a single 65 piece. Returning to Figs. 3, 4, 5, and 29 to 31 inclusive, the forwardly extending arm 245 carries, upon its left-hand side, an anti-friction roller 246. The roller 246 is adapted, generally, to follow the periphery of the card-stop control-cam 70 130. The rear end of the rock-arm 243 pivotally supports the top of a short link 247 which link is pivoted to the rear end of a card-stop actuating-arm 248 as is old and well known. A card-stop 249, for the master-cards, and a card-stop 250, 75

for the detail cards, work together and individually as follows:

For every revolution of the main shaft 52, the push-link 233 will be moved up and down once. This will positively open and close the card-stop 249 so that any master-card, fed into the master-card sensing chamber, will only remain in the chamber for one machine cycle. It will, further, be noted that the card-stop 249 will operate on every machine cycle whether there are any cards in the master-card sensing-chamber or not. If the machine is running with the card-stop control-cam 130 in its normal position, shown particularly well in Fig. 29, then the rearwardly extending nose 241, of arm 238, will engage the pin 242 and operate the card-stop 250 simultaneously with the card-stop 249. In this event, the roller 246 will be idly returned to and lifted from a low part of cam 130. If, however, the cam 130 should be swung one-eighth of a revolution, to the position shown in Fig. 30, then the roller 246 would be held upon one of the high parts of cam 130 and would keep the card-stop 250 closed, regardless of the action of card stop 249. The machine, in this condition would retain a detail-card in its sensing chamber and would continue to feed master-cards until one was found that agreed with the detail-card being held. The control unit would then be rotated one-eighth of a turn back to normal position and the card-stop control-cam 130 would again assume the position shown in Fig. 29. In the Fig. 29 position, of the cam 130, the machine will continue to feed only detail-cards until a detail-card that does not compare with the master-card enters its sensing chamber.

Sensing

Particular reference is here made to Figs. 3 to 8 inclusive. From these figures, it is seen that the reciprocating detail-card pin-box, designated generally herein by the reference numeral 255, is supported and motivated by the usual eccentric and strap arrangement which is also well shown in Figs. 16 and 17. As this arrangement is so old and well-known in the art, the eccentric and strap assembly, just mentioned, will be designated as a whole by the reference numeral 256. The reciprocating pin-box is guided for vertical movement by the usual upright posts 257. The reciprocating pin-box for the master-cards which is designated herein by the numeral 258 is similar to the pin-box 255 and, consequently, need not be described. A series of small, manually operable, locking pieces 259 (one for each column) are depressible to hold one or more of the locking slides 260 in inactive position, in case this might be desired. By using the locking pieces 259, any column or columns of data in the master-cards can be preselected for transfer to the detail-cards. In other words, when it is not desirable to transfer certain columns of data, the locking pieces 259, associated with those columns of data, are depressed while the machine is at rest. Then, when the machine is started, the disabled pins in the reciprocating master-card sensing head will not depress their associated pins in the stationary pin-box M. The pin box 258 is moved up and down by two eccentric and strap assemblies 261, one on each side of the pin box. Long rods 262 connect the eccentric assemblies 261 with the pin box 258. The assemblies 261 are held upon the secondary operating shaft 55. The shaft 55 is geared in exactly the same ratio to the motor as the main operating shaft 52. The arrangement

of the parts is such that, as the pin-box 255 is lowered the pin-box 258 is raised so that both pin boxes sense at the same time. There are two sets of complementary cams which also operate from the shaft 55 but these cams are for reciprocating the punch head and will, therefore, be described in detail later. However, Fig. 20 shows the relative positions of the complementary cams and eccentric assemblies 261 upon the shaft 55.

The pin-box 255 has a means (including a pin 263, Fig. 4) for keeping the locking slides in ineffective position when the detail-card magazine is empty which means is identical to that shown in Figs. 9 and 10 of the Patent 2,044,119 to Lasker wherein a pin 204 is the exact equivalent of the pin 263 in the present invention. A functionally similar arrangement applies to the pin-box 258. As is best shown in Figs. 6, 21 and 21A, a retract bail bar 265 for the locking slides 260 is pivotally mounted upon a shaft 266 by a pair of bail-arms 267; one at each end of the bail-bar 265. The arms 267 are pressed clockwise, as seen in Fig. 6, by springs 268. Mounted upon and fast to the shaft 266 is a pair of short stop arms 269 which arms have bent over ears 270. A lever 271, pivoted to the pin box 258 at 272, is connected at its forward end, to a pin 263A (shown dotted in Fig. 21) which is just like the pin 263, shown in Fig. 4. As can most easily be seen from Fig. 21, a strip or bar 273 connects the lever 271 with a lever 274 (see also Fig. 12). From the foregoing it will be evident that, if there are no cards in the master-card sensing chamber, the levers 271 and 274 will be in their Fig. 6 and 11 positions and will be engaging and holding the ears 270 on the stop-arms 269. In this position the bail bar 265 (see Fig. 6) will be pressing all the locking slides 260 into their inactive or forward positions. However, as soon as a card enters the master-card sensing-chamber, the lever 271 will be swung counter-clockwise, as seen in Fig. 6, and this will allow the bail bar 265 to swing clockwise far enough so as to allow anti-friction rollers 275 to work against a pair of fixed cam edges 276 in the same manner as is done with the detail-card reciprocating pin-box 255.

As has been previously explained, the stationary pin-box for the master-cards, (which is designated by the letter M), contains the locking slides 226 and the retract bail 228. A master-card will remain in its sensing chamber for one cycle only. However, the punchings on a master-card will be transferred to the pins of the stationary master-card pin-box and will remain locked therein until the retract bail 228 is operated to release them. The stationary detail-card pin-box, (which has been designated previously by the letter D), has pins which carry no extrusions upon their sides. There is, therefore, no retract mechanism for this box. Actual comparison sensing is accomplished as follows:

Assume that the necessary interponents 106 (Fig. 6) have been raised to their active positions and that the dial 10 (see Fig. 10) has been set to its "Compar" position. The machine will now act as a "comparing reproducer."

Referring particularly to Figs. 6, 7 and 8, the first operating cycle will feed a detail-card into its sensing chamber. No master-card will be fed on this first cycle, as was explained under the heading "Card feed." At the end of the cycle the detail-card pin-box 255 will sense the detail-card and the master-card pin-box 258 will

come down into sensing position. Certain pins, in the pin-box 255, will come up through the designation holes in the detail-card and will push up corresponding pins 289, held in the 5 stationary pin-box D. The pins 280 will, in turn, push up pins 281 in the foremost unit T¹ of two removable translator units. The pins in either translator T¹ or T² may be arranged to suit the user's needs just as the translator units for 10 the Powers tabulators are wired in different ways. The pins 281, upon being elevated, will elevate corresponding pins 282 in the forward section of a comparison unit C. The upward motion of the pins 282 is transmitted, through a plurality of centrally pivoted rock-levers 283, to corresponding pins 284 in the rear section of the comparison unit C. There is one lever 283 for each pin 282. One-half of the levers 283 lie on 15 the right-hand side of the pins 282 and the other half lie on the left-hand side. This arrangement of the levers 283 is necessary because it was desired to make the height of the comparison unit as small as possible. When the pins 284 are depressed, by the pins 282, they are not 20 depressed an amount equal to the rise of the pins 282 because there is a certain amount of lost motion in the slots in the ends of the levers 283. The relative movement of the pins 282 and corresponding pins 284 is best understood by 25 detailing the motion of the pins as follows:

When a pin 282 is pushed up by a corresponding pin in the pin-box 255, it is raised until an extrusion 285, thereon, rests above the cam point 286 on front of the associated comparison slide 35 107. But the pin 282, acting through a second extrusion 287 and a lever 283, pushes down a corresponding pin 284 just far enough so that an extrusion 288, thereon, will rest against the high point of a cam edge 289, thus holding the slide 40 107 in its forward or active position at the end of the cycle. As was previously explained, in connection with the control unit, the cam shaft of the control unit will be revolved one-eighth of a turn from normal if a comparison slide is 45 in its active position. Therefore, at the end of the first machine cycle, the machine is conditioned to revolve the control-unit cam shaft at the very beginning of the second cycle.

On the first operating cycle, the second detail-50 card will remain in its sensing-chamber and the first master-card will be fed. At the end of this cycle both cards will be sensed simultaneously and, if they do not compare exactly as to designation punchings, the detail-card will still be held 55 and master-cards, only, will be fed, on subsequent cycles. However, when a master-card is found that agrees with the first detail-card then the pins of the master-card pin-box 258 will push down corresponding pins 284 far enough so that 60 their extrusions 288 will travel down below the cam points 289. It is thus seen that, when both sensing heads are pressing exactly corresponding pins 282 and 284 at exactly the same time, all the extrusions 285 and 288 will be respectively above 65 and below the cam points on the comparison slides 107. Hence, at the end of such an operating cycle, the comparison slides 107 will be in their rearward or inactive positions and the machine will be conditioned to rotate the control-unit cam-shaft one-eighth of a turn, back to 70 normal position on the very first part of the next succeeding cycle.

It is, thus, generally understood how sensing and comparing is accomplished in the present 75 machine and a complete card-run will be given,

with all machine functions under the heading "Summary of operations."

Punch unit

As is shown in Figs. 5, 8, 11 and 20, the punch unit has its own card-stop mechanism, retract mechanism and reciprocating mechanism and it is to be particularly noted here that these mechanisms operate on every cycle and are independent of the control unit. Referring particularly to Figs. 5, 8, and 20, it is seen that, fast upon the secondary operating shaft 55, two sets of complementary cams 291 are mounted. The cams 291 lie just inside the eccentric and strap assemblies for the master-card pin-box 258 as is most clearly shown in Fig. 20. Associated with each set of complementary cams 291 is a follower 292 consisting of two yoke-shaped plates joined by pins 293 and having follower rollers 294. The plates 292 are supported upon short stub-shafts 292A which extend from the side frames 4 and 6. The upper pins 293 pivotally support the lower ends of push-links 295. The upper ends of the push-links 295 are pinned to the lower ends of rods 296. The upper ends of rods 296 are shouldered and threaded and, as is particularly well shown in Fig. 5, these rods 296 are securely fastened to end castings 297. The castings 297 are made with lugs on their inner (toward the middle of the machine) sides and through these lugs run screws 298 (see Fig. 20) which thread into and hold a plate 299. Secured to the end castings 297 are front and rear plates 300 and top and bottom guide plates 301. Between the guide plates 301 are rows of lock-pins 302 which are constantly urged upward by coiled springs 303. Between each row of pins 302 is a set of two locking slides 304 (see particularly Fig. 8). The locking slides 304 are individually spring pressed toward the rear of the machine, as shown, and a retract bail bar 304 operates them simultaneously just before the middle of each operating cycle.

The punch unit also contains a single-piece stationary casting 306 and this casting 306 is supported, at each side, by a support plate 307 (see particularly Fig. 20), screwed or otherwise suitably fastened to the side castings 4 and 6. The casting 306 supports a top plate 308 (Fig. 8) and also a plate 309. The plates 308 and 309 are 50 merely detent plates to hold cards while they are being punched. It will here be noted that the reciprocating rods 296 (Fig. 20) run through the casting 306 and are guided by it.

Referring particularly to Figs. 5, 8, 11 and 20, it is seen that the retract bail for the punch is 55 operated by cam 51 (Fig. 11). Just previous to the middle of each cycle, the high point of the cam 51 strikes a follower roller 310, carried upon the right-hand side of a rock-lever 311 which 60 lever is pivoted at 312 to the frame casting 4. The forward end of the rock-lever 311 pivotally supports the lower end of a link 313. The upper end of link 313 is pivotally connected to the forwardly extending end of a lever 314. Lever 314 65 is fast upon the left-hand end of a rock-shaft 315 and this shaft is journalled in brackets 316, the right-hand one of which, as seen in Figs. 19 and 20, is screwed to the right-hand translator-supporting-rail. The left-hand bracket 316 is 70 screwed to the left-hand translator-supporting-rail. An angle-bracket 317 (see Fig. 11) supports the left-hand end of the shaft 315. As can most easily be seen in Figs. 8 and 20, the shaft 315 has rigidly mounted, thereon, a pair of depending 75

arms 318 and these arms carry anti-friction rollers 319 which rollers are adapted to engage a pair of depending arms 320. The arms 320 hold the retract bail-bar 305 and they are fast upon a rock-shaft 321. The rock-shaft 321 is journaled in a pair of brackets 322 which are best shown in Fig. 20. The brackets 322 are securely fastened to the rear punch plate 300. The retract bail 305 reciprocates with the punch pin-box and it is for this reason that the arms 318 are used to operate it.

The card-stop mechanism for the punch unit is operated from the cam 56 (see Fig. 11) on the left-hand end of the secondary operating shaft 55. The cam 56 operates to open the card-stop, for the punch, at the same time as the card-stops for the master-card sensing-chamber and the detail-card sensing-chamber. The cam 56 acts upon a follower roller 325, held upon the right-hand face of a rock-arm 326 which arm is fast upon the extreme left-hand end of a shaft 327. The shaft 327, as can best be seen in Figs. 8 and 20, extends laterally across the rear of the machine and is journaled in the inner walls of the frame castings 4 and 6. Fast upon shaft 327 is a pair of arms 328 which arms are pivotally connected, at their forward ends, to a pair of upright links 329. The upper ends of links 329 are connected to the offset bottoms of a pair of stop-strips 330. These strips 330, together, constitute the card stop for the punch and they are urged upward by a pair of springs 331 anchored, at their lower ends, to a pair of pins 332, held by the strips 330, and anchored, at their upper ends to headed studs 333, held in the stationary casting 306. The strips 330 are supported for vertical sliding movement in grooves in the rear of the stationary punch-casting 306 and are held to the punch-casting 306 by the headed studs 333 and screws 334 in the usual manner.

A funnel-shaped receiver 335 is securely fastened to the frame casting 3 and is for the purpose of receiving the punchings dropped from above.

Manual control of machine functions

Referring to Figs. 16, 21A, 24, and 27, it is seen that the dial 10 is pivotally mounted in the frame casting 8. The dial carries, upon its left-hand side, a cam 340 and a detent cam 341. The detent cam 341 cooperates with a roller 342, carried upon a detent arm 343 which arm is pivoted to the frame 8. A forwardly extending arm 344 carries a roller 345 which roller cooperates with the cam 340. A spring 346 constantly draws the rollers 342 and 345 against their respective cams. The arm 344 is securely fastened upon the extreme left-hand end of a short shaft 347, pivotally supported by the frame casting 8. Fast upon the opposite end of shaft 347, is the bell-crank 187-188.

When it is desired to reproduce the punchings of a series of master-cards upon a series of unpunched or blank cards, it is necessary to allow cards to be simultaneously fed from both magazines. It is also necessary to cause the retract bail for the master-card sensing-head to operate at each cycle. These results are accomplished by manually setting the dial 10 to the Fig. 27 position where it will show "Plain". Here the dial, acting through cam 340, has rocked the bell-crank 187-188 a small distance clockwise which, in turn, has raised the links 174 and 170 to such a position that the hooks 190 and 191 no longer hold the pins 194 on the slides 157 and, consequently,

both the master-card and detail-card pickers are allowed to feed in unison. Referring to Figs. 27 and 24 together, it is further seen that, when the cam 340 is in the Fig. 27 position, the arm 188 is positively holding the link 218 in its rearmost position (not shown). In this position the link 218 holds the lever 207 away from its cam 131 and this also holds the link 211 in its rearmost position. In this position, the link 211, through spring 217, holds the hook 214A under the pin 10 222. Consequently, the retract link 216 is operated once for each operating cycle of the machine.

Summary of operations

Assume, for the sake of illustration, that it is 15 desired to make full duplicates, from blank cards, of a stack of so-called master-cards. These master-cards may be any punched cards, bearing designation punchings and data punchings.

First, the master-cards are sorted sequentially 20 in regard to designation punchings. Then they are inserted in the master-card magazine of the present machine and the blank cards are inserted in the detail-card magazine. The motor switch S (Fig. 16) is turned on to start the electric motor. 25 The latches 66 and 85 on the card magazines are not depressed but are left in their Fig. 22 positions. The dial 10 is turned to the position where it reads "Plain". All the interponents 106 are left in their lower inactive positions, shown in Figs. 6 and 7. The stop-start button 60 is pressed in and the machine begins to operate. The moving of the dial 10 has positioned, as has been explained in connection with Fig. 27, the hooks 190 and 191 so that they do not interfere with the pins 194 on the slides 157 and both pickers will operate together. Therefore, a master-card and a blank-card will be fed together, into their respective sensing chambers on the first half of the first operating cycle. Referring to the composite views which include Figs. 3, 4, 5, 6, 7, and 8, it is seen that, in the last half of the first operating cycle, the pin boxes 255 and 258 come to sensing position and, since the master-card is the only perforated card, the pins 280 and the pins 281 (Fig. 7) will remain unmoved. However, 45 certain pins, corresponding to the master-card punchings, will be depressed and locked in the stationary master-card pin-box M. These, in turn, will depress corresponding pins 284, in the rear section of the comparison unit C, and the extrusions 288, thereon, will be lowered past the cam points 289 on the comparison slides 107. Also a second set of extrusions 284A will rock levers 283 counter-clockwise. The rocking of levers 283 will lift pins 282 to a position where extrusions 285 will rest directly upon the cam points 286 of their slides 107, thus moving the slides 107 toward the front of the machine. The slides 107, however, will have no effect upon the bail bar 104 because the interponents 106 were 50 all depressed to their ineffective positions before the first cards were fed. The depression of the pins 284 also caused depression of corresponding pins 281A which pins are held in the frames of a removable translator unit T2. The pins 281A 55 which have been depressed will remain so until almost the very end of the next or second operating cycle because the retract bail 228, when it is operated, is operated at the end of a cycle.

Since the movements of the comparison slides 70 107 do not affect the bail bar 104, when the machine is set for plain reproducing, the cams 130, 131 and 132, on the control unit, will remain in their normal Fig. 4 position no matter how many cards are reproduced. Because of this, the card 75

stops for the master-card and detail-card sensing-chambers will operate in unison and will operate at every cycle.

Also, since the dial 10 was moved to its "Plain" 5 position, the bell-crank 187-188 (see Fig. 4) was swung clockwise from its Fig. 24 position. This moved the link 218 and the link 211 toward the rear of the machine to position the hook 214A, on lever 214, under the pin 222. Thus, it will be 10 understood that the retract bail 228, on the master-card pin-box M, will operate at every cycle.

In the first half of the second cycle, the first master-card is rolled into its receiving pocket 16, 15 the first blank card will be rolled into the punch chamber, the second master-card will be fed into its sensing chamber, and the second blank card will be fed into the detail-card sensing chamber. At the middle of this second operating cycle, 20 the reciprocating punch pin-box is in its uppermost position and in this position certain pins 302 are depressed by corresponding pins 281A of the rear translator unit T2. As soon as the pins 302 are depressed, they are locked by the slides 304. 25 Thus, at the middle of the second operating cycle, all the punchings held on the first master-card have been transferred to and locked in the punch pin-box.

On the second half of the second operating 30 cycle, the punch pin-box and the plate 299 descend with the master-card pin-box 258 and the depressed pins 302 will contact corresponding punch-pins 302A and push them through the first blank card. At almost the end of the second 35 cycle, the retract bail 228, for the stationary master-card pin-box M, releases its entire train of pins (including the pins 284 and the pins 281A); and the reciprocating master-card pin-box 258 is in sensing position. Since the pin-box 40 258 is now sensing the second master-card, it will, at this time be depressing, and holding depressed, those new pins which correspond to the punchings in the second master-card and, when the second operating cycle is completed, these newly-depressed pins will be locked by the slides 260 and will not be released until almost the end of the third cycle as has been explained.

Just before the middle of the third cycle the 45 retract bail 305, for the punch, releases all the pins 302.

The third cycle and all subsequent cycles are 50 repetitions of the second cycle. In the third cycle the second master-card will be rolled into its receiving pocket 16; the third master-card will be fed into its sensing chamber; the first blank-card (which is now punched according to the first master-card) will be rolled into its receiving pocket 18; the second blank-card will be rolled into the punch-chamber; and the third blank-card will be fed into the detail-card sensing-chamber. From the foregoing, it is understood 55 that the machine will continue to operate until the master-card magazine is empty at which time it will automatically stop, due to the latch 66. Thus the machine, after stopping, will hold the last master-card in its sensing chamber and will also hold one (punched) blank card in the punch chamber and one blank-card in the detail-card sensing chamber. At this point, any blank cards 60 which may be in the detail-card magazine are manually removed and the stop-start button is then pressed in. This operates the machine for one cycle and ejects the last master-card and the punched blank-card. It also feeds the last blank-card into the punch chamber and punches 65 70 75

it. The stop-start button is again pushed in and the machine operates for one cycle to eject the last card.

Assume now, that it is desired to reproduce the so-called "data" punchings of a set of master cards, bearing both "data" and "designation" 5 punchings, upon a series of detail-cards which have been pre-punched for "designations" and which may or may not hold "data" punchings of their own. Assume that it is desired to compare each master-card with each detail-card so that the "data" on any given master-card will be transferred only to the detail-card or cards which agree (as to designation) with that given master-card.

First the master-cards and detail-cards are sorted sequentially according to designation and they are then inserted in their respective magazines. Referring particularly to Figs. 3 to 8, inclusive, the interponents 108 for each column of 20 the predetermined designation field are manually raised to their active positions. The latch 66, for the master-card magazine, is manually depressed to its Fig. 3 position and the latch 85 for the detail-card magazine is left in its "up" 25 position, shown in Fig. 22. It is necessary to have the latches 66 and 85 arranged in this manner because it often occurs that there is a greater number of detail-cards than master-cards. There may be many detail-cards, whose "designation" 30 punchings are identical but whose "data" punchings are different and it will be desired to punch each of these cards from a single master-card which agrees with them only as to "designation" punchings. Thus, the number of detail-cards is sometimes so great as to exceed the capacity of the magazine. When this is the case, it is desirable to stop the machine as soon as the detail-card magazine is empty.

The dial 10 is turned so that it shows "Comp." 40 This, as was explained in connection with Fig. 24, conditions the machine so that it will feed from either the master card or the detail-card magazine under control of the comparison unit. As the cams 130 to 132, inclusive, of the 45 control unit, are now in their normal or Fig. 4 position, the machine will start feeding from the detail-card magazine only. The stop-start button 60 is now pressed in and the first "comparison reproducing" cycle begins.

On the first cycle the first detail-card is fed 50 into its sensing chamber and is sensed. Those pins, held in the reciprocating pin-box 255, which find holes, come through and push up corresponding pins 280 in the well-known manner. The 55 pins 280, in turn, elevate corresponding pins 282 to partially depress corresponding pins 284. The pins 284, however, are depressed to just the point where their extrusions 288 lie against the middle of the cam points 289 on the comparison slides 60 107 with the result that the slides are moved toward the front of the machine and they cause the bail bar 104 to be swung clockwise about shaft 102. This, as is best seen in Fig. 35, causes the lever 99 to assume the position shown therein, at 65 the end of the first operating cycle.

On the very first part of the second operating 70 cycle, the ratchet-actuating arm 110 will be immediately swung clockwise by link 115. This will allow the pawl 122 to engage the teeth of its associated ratchet disc 95 and move the cam shaft 92 one-eighth of a turn clockwise to position the cams 130, 131 and 132 as is shown in Fig. 30. Thus the card-stop cam 130 will hold the card-stop 250 closed; the retract cam 131 will hold the 75

arm 207 (Fig. 24) in such a position that the link 211 holds the hook 214A under the pin 222; and the card feed cam 132 will be in its Fig. 25 position wherein it will allow only master-cards to feed.

Therefore, at the end of the second operating cycle, the first master-card will have been fed into its sensing chamber and sensed, and the first detail-card will be locked in its sensing chamber. The machine will continue to feed master-cards, provided the first master-card does not agree with the first detail-card in designation punchings, until a master-card whose designatory punchings are the same as those of its first detail-card, enters the sensing-chamber. At the end of such a cycle, which, for the sake of illustration, shall be the eighth machine cycle, the comparison slides 107 remain in their rear or Fig. 6 positions and thus, as is best shown in Fig. 34, the ear 99A, on the lever 99, will have followed the lever 110 and will be resting thereupon. At the very beginning of the next succeeding cycle, the push-link 115 will immediately rise, as is shown in Fig. 33, and the bell-crank 97 will assume the position shown therein. Thus, the pin 129, on slide 128, has held the pawl 122 ineffective and has permitted the pawl 120 to engage the teeth of its ratchet disc 94 to turn the cam shaft 92 one-eighth of a turn. The position of shaft 92, thus attained, is equivalent to normal position as the cams 130, 131 and 132 each have four equal and evenly spaced high points. Therefore, the machine will operate to feed only detail-cards on this ninth cycle. Furthermore, since the retract cam 131 (Figs. 4 and 24) has been returned to normal, the set up in the stationary pin-box M, which was entered by the agreeing master-card, will remain locked therein, even though the master-card is fed into its receiving pocket 16 at the middle of the ninth cycle and no new master-cards are fed. The reason for this is that while the retract bail, for the stationary pin-box M, was operated near the end of the eighth cycle, the pins were immediately relocked. Therefore, the pin set-up obtained from the master-card remained locked in the pin-box M during the ninth cycle. At the first part of the ninth cycle the retract cam 131 was turned one-eighth of a revolution to render the retract bail 228 (Fig. 6) ineffective and, therefore, the pin set-up remains until the retract bail again operates.

From the foregoing it is evident that, as long as the designation punchings of the detail-cards agree with the locked-in pin set-up, the machine will continue to feed only detail cards. It will, further, be evident that, when master-cards and detail-cards do not agree in designatory punchings, master-cards, only, will be fed.

As soon as the last detail-card leaves its magazine, the machine will automatically stop. It is then necessary to push in the stop-start button twice to run this last card into the punch chamber, and then out into its receiving pocket 18. On the next to the last manually-induced operating cycle, the set-up locked in the stationary pin-box M will, of course, not compare or agree with the pins in the detail-card sensing head because there is no card in the detail-card sensing-chamber. Hence the control unit cam-shaft 92 will be revolved one-eighth of a turn on the last manually induced cycle, and, at the end of this cycle, the retract bail 228 (Fig. 6) will release all the pins in the stationary pin-box M.

While I have described what I consider to be a highly desirable embodiment of my invention,

it is obvious that many changes in form could be made without departing from the spirit of my invention, and, I, therefore, do not limit myself to the exact form herein shown and described, nor to anything less than the whole of my invention as hereinbefore set forth, and as hereinafter claimed. 5

What I claim as new, and desire to secure by Letters Patent, is:

1. A machine of the class described, the combination of two card magazines, two card-sensing means, one for each of the magazines, means for feeding cards from one of said magazines to its associated sensing means, separate means for feeding cards from the other magazine to its associated sensing-means, means for automatically stopping said machine on a cycle when no card is fed to the first-mentioned sensing-means; manually-settable means, associated with one of the magazines, for stopping said machine when that magazine runs empty; and separate manually-settable means, associated with the second magazine, for stopping said machine when the second magazine runs empty. 15

2. In a machine of the class described, the combination of two separate card-sensing means each including a reciprocatory pin box and a stationary pin box, means for feeding cards to and from said card-sensing means, means for locking the sensings of one of said reciprocatory pin 30 boxes in its associated stationary pin box for a number of machine cycles, and means for automatically unlocking said stationary pin box.

3. In a machine of the class described, the combination, with main operating mechanism for said machine, of card-sensing means including a reciprocatory pin box operable thereby and a stationary pin box, means for locking the sensings of said reciprocatory pin box in said stationary pin box for a number of machine cycles, a second and separate card-sensing means, means for comparing the designation sensing of both of said sensing means at every operating cycle, means for unlocking said stationary pin box when the designation sensings of both sensing means are 45 not identical, manually settable means for disabling the designation-comparing-means, and manually settable means for causing said stationary pin box to be automatically unlocked at every operating cycle. 50

4. In a machine of the class described, the combination of card-sensing means, a second and separate card-sensing means, means for feeding cards to both of said card-sensing means; a card stop associated with said first-mentioned card-sensing means, for intermittently retaining and releasing cards; a separate card stop, associated with said second mentioned card-sensing means, for intermittently retaining and releasing cards; automatically operable means for causing one 60 of the card stops to hold a card for a number of machine cycles, and manually operable means for causing both card stops to operate in unison. 55

5. In a machine of the class described, the combination with main operating mechanism, of 65 card-sensing means operable thereby and including a plurality of settable pins, mechanism for locking said settable pins in set position, a second card-sensing means, and mechanism for comparing preselected sensings of the first-mentioned card-sensing means with preselected sensings of the second-mentioned card-sensing means including a slide device operable by both said card-sensing means for controlling the locking mechanism. 70

6. In a machine of the class described, the combination with main operating mechanism for said machine, of card-sensing means operable thereby and including a plurality of settable pins, 5 means for locking said pins in set position, a second card-sensing means, mechanism for comparing the sensings of both sensing means including a slide device, mechanism for feeding cards to one of said card-sensing means, a separate mechanism for feeding cards to the other of said card-sensing means, card-stop mechanism for both of said sensing means; and means, controllable by the comparing mechanism, for controlling the pin-locking means, both of the 10 card-feeding mechanisms and the card-stop mechanism.
7. In a machine of the class described, the combination of a plurality of sensing mechanisms, a respective card-feeding device for feeding cards to each of said sensing mechanisms, and a device movable to respective positions for rendering any of the feeding devices effective singly and to another position for rendering a plurality of the feeding devices concomitantly 15 effective for a number of machine cycles.
8. In a machine of the class described, the combination of a plurality of sensing mechanisms, a respective card-feeding device for feeding cards to each of said sensing mechanisms, and a device movable to respective positions for rendering any of the feeding devices effective singly and to another position for rendering a plurality of the feeding devices simultaneously effective for a number of machine cycles.
9. In a machine of the class described, the combination of a plurality of sensing mechanisms, a respective card-feeding device for feeding cards to each of said sensing mechanisms, and a device automatically movable to respective 20 positions for rendering any of the feeding devices effective singly and manually settable to a position for rendering a plurality of feeding devices concomitantly effective for a number of machine cycles.
10. In a machine of the class described, the combination of two separate card-sensing means, power-driven rollers for conveying cards to said sensing means, two separate card-pickers for feeding cards to said rollers; a pair of slides, each slide associated with a separate card-picker, for operating said card-pickers; main operating mechanism for said machine including a main operating shaft, a cam on said main operating shaft, and intermediate means operable by said cam for actuating said slides.
11. The combination of two separate card-pickers for feeding cards; a pair of slides, each slide associated with a separate card-picker, for operating said card-pickers; main operating mechanism for said machine including a main operating shaft, a cam on said main operating shaft, intermediate means operable by said cam for actuating said slides; a pair of latches, movable to a plurality of positions and associated with said slides, for holding either slide inactive while the other is active; and means for manually positioning said latches to allow both of said slides to act simultaneously.
12. The combination of two separate card-pickers for feeding cards; a pair of slides, each slide associated with a separate card-picker, for operating said card-pickers; main operating mechanism for said machine including a main operating shaft, a cam on said main operating shaft, intermediate means operable by said cam for actuating said slides; a pair of latches, movable to a plurality of positions and associated with said slides, for holding either slide inactive while the other is active; means for comparing the sensings of both of said card-sensing means, and means controllable by the comparing means for automatically positioning said latches to hold first one and then the other of said slides inactive.
13. The combination of two separate card-pickers for feeding cards; a pair of slides, each slide associated with a separate card-picker, for operating said card-pickers; main operating mechanism for said machine including a main operating shaft, a cam on said main operating shaft, intermediate means operable by said cam for actuating said slides; a pair of latches, movable to a plurality of positions and associated with said slides, for holding either slide inactive while the other is active; means for comparing the sensings of both of said card-sensing means, means controllable by the comparing means for automatically positioning said latches to hold first one then the other of said slides inactive, and means for manually positioning said latches to allow both of said slides to act simultaneously.
14. In a machine of the class described, the combination of two card-sensing mechanisms, two mechanisms for feeding cards to said card-sensing mechanisms, means for comparing pre-selected sensings of both of said sensing mechanisms, a cam-shaft, a cam fast on said shaft for controlling the card-feeding mechanisms, and means under control of the comparing mechanism for operating said cam-shaft.
15. In a machine of the class described, the combination of two card-sensing mechanisms, card stop mechanism for said sensing mechanisms, means for comparing preselected sensings of both of said sensing mechanisms, a cam-shaft, a cam fast on said shaft for controlling said card stop mechanism, and means under control of the comparing mechanism for operating said cam-shaft.
16. In a machine of the class described, the combination of a card-sensing means including a reciprocatory pin-box and a stationary pin-box, means for locking the sensings of said reciprocating pin box in said stationary pin box, means for unlocking said stationary pin box, a second card-sensing means, mechanism for feeding cards to and from both the card-sensing means, means for comparing the sensing of both sensing means, a cam-shaft, a cam fast on said cam-shaft for controlling the unlocking of said stationary pin box, and means under control of the comparing means for operating said cam-shaft.
17. In a machine of the class described, the combination of two separate card-sensing mechanisms, a set of pins associated with and movable by one of said sensing mechanisms, a separate set of pins associated with and movable by the other of said sensing mechanisms, and a device whereby a full movement of any of the pins of either of said sets of pins will cause a lesser movement of a corresponding pin in the other of said sets of pins.
18. In a machine of the class described, the combination of two separate card-sensing mechanisms, a set of pins associated with and movable by one of said sensing mechanisms, a separate set of pins associated with and movable by the other of said sensing mechanisms, and a slide operable by any of the pins of either of said sets of pins.

19. In a machine of the class described, the combination of two separate card-sensing mechanisms, a set of pins associated with and movable by one of said sensing mechanisms, a separate set of pins associated with and movable by the other of said sensing mechanisms, a device for controlling machine operations, means for actuating said device, and a slide operable by any of the pins of said sets of pins for controlling the 10 operation of said actuating means.

20. In a machine of the class described, the combination of two separate card-sensing mechanisms, a set of pins associated with and movable by one of said sensing mechanisms, a separate set of pins associated with and movable by the other of said sensing mechanisms, and a plurality of levers whereby a full movement of any of the pins of either of said sets of pins will cause a lesser movement of a corresponding pin in the 20 other of said sets of pins.

21. In a machine of the class described, the combination of two card-sensing mechanisms, two mechanisms for feeding cards to said card-sensing mechanisms, means for comparing the 25 sensings of both of said card-sensing mechanisms, a cam-shaft, a cam on said shaft for controlling the card-feeding mechanisms, a pair of ratchet-wheels mounted on said cam-shaft, and means under control of the comparing means 30 for operating said ratchet-wheels.

22. In a machine of the class described, the combination of two card-sensing mechanisms, two mechanisms for feeding cards to said card-sensing mechanisms, means for comparing the 35 sensings of both of said card-sensing mechanisms, a cam-shaft, a cam on said shaft for controlling the card-feeding mechanisms, a pair of ratchet-wheels mounted on said cam-shaft, a pawl operable to actuate one of said ratchet-wheels, another pawl operable to actuate the 40 other of said ratchet-wheels, and means under control of the comparing means for rendering first one and then the other of said pawls active.

23. The combination of a card-sensing means 45 including a plurality of settable pins, a second card-sensing means, means for comparing preselected sensings of one of said sensing means with preselected sensings of the other of said sensing means, and means under control of said 50 comparing means for locking said pins in set position and for unlocking said pins.

24. The combination of card-sensing means including a plurality of settable pins, mechanism for locking said pins in set position, a second 55 card-sensing means, means for comparing preselected sensings of one of said sensing means with preselected sensings of the other of said sensing means, and means under control of said 60 comparing means for rendering said locking mechanism effective and ineffective.

25. The combination of a card-sensing means including a plurality of settable pins, mechanism for locking said pins in set position, a second card-sensing means, means for comparing preselected sensings of one of said sensing means 65 with preselected sensings of the other of said sensing means, means for rendering said locking mechanism effective and ineffective, and means under control of said comparing means for enabling and disabling the last-mentioned means.

26. The combination of a card-sensing means including a plurality of settable pins, mechanism normally active in one direction to lock said pins in set position, a second card-sensing means, 70 means for comparing preselected sensings of one 75

of said sensing means with preselected sensings of the other of said sensing means, means for rendering said locking mechanism effective and ineffective, and means under control of said comparing means for enabling and disabling the 5 last-mentioned means.

27. In a machine of the class described, the combination, with main operating mechanism for said machine, of card-sensing means including a reciprocatory pin box operable thereby and a stationary pin box, means for locking the sensings of said reciprocatory pin box in said stationary pin box for a number of machine cycles, a second and separate card-sensing means, means for comparing the designation sensing of 10 both of said sensing means at every operating cycle, means for unlocking said stationary pin box when the designation sensings of both sensing means are not identical, manually settable means for disabling the designation-comparing 15 means, and means for causing said stationary pin box to be automatically unlocked at every operating cycle.

28. In a machine of the class described, the combination, with main operating mechanism 25 for said machine, of card-sensing means including a reciprocatory pin box operable thereby and a stationary pin box, means for locking the sensings of said reciprocatory pin box in said stationary pin box for a number of machine cycles, 30 a second and separate card-sensing means, means for comparing the designation sensing of both of said sensing means at every operating cycle, and means for unlocking said stationary pin box when the designation sensings of both 35 sensing means are not identical.

29. The combination of card-sensing means including a reciprocatory pin box and a stationary pin box, means for locking the sensings of said reciprocatory pin box in said stationary pin 40 box for a number of machine cycles, a second and separate card-sensing means, means for comparing the designation sensings of both of said sensing means at every operating cycle, means for unlocking said stationary pin box 45 when the designation sensings of both sensing means are not identical, and means for causing said stationary pin box to be unlocked at every operating cycle.

30. In a machine of the class described, the 50 combination of card-sensing means including a reciprocatory and a stationary pin box, a second and separate card-sensing means including a reciprocatory and a stationary pin box, means for feeding cards to both of said card-sensing 55 means; a card stop associated with said first-mentioned card-sensing means, for intermittently retaining and releasing cards; a separate card stop, associated with said second-mentioned card-sensing means, for intermittently retaining 60 and releasing cards; automatically operable means for causing one of the card stops to hold a card for a number of machine cycles, and manually operable means for causing both card stops to operate in unison. 65

31. The combination of card-sensing means, a second and separate card-sensing means, means for feeding cards to both of said card-sensing means, means for comparing preselected sensings of said sensing means, a card stop associated 70 with the first-mentioned card-sensing means for intermittently retaining and releasing cards, a separate card stop associated with the second-mentioned card-sensing means, means under control of said comparing means for causing one 75

of said card-stops to hold a card for a number of machine cycles, and means for causing both card-stops to operate in unison.

32. The combination of card-sensing means, 5 a second and separate card-sensing means, means for feeding cards to both of said card-sensing means, means for comparing preselected sensings of said sensing means, a card stop associated with the first mentioned card-sensing 10 means for intermittently retaining and releasing cards, a separate card stop associated with the second mentioned card-sensing means, means under control of said comparing means for causing one of said card-stops to hold a card for a 15 number of machine cycles, and manually operable means for causing both card-stops to operate in unison.

33. The combination of card-sensing means including a plurality of settable pins, mechanism for locking said settable pins in set position, 20 a second card-sensing means, mechanism for comparing preselected sensings of the first-mentioned card-sensing means with preselected sensings of said second card-sensing means including a slide 25 device, and means controllable by said slide device for varying the timing of the operation of said locking mechanism.

34. The combination of card-sensing means including a plurality of settable pins, mechanism 30 for locking said settable pins in set position, a second card-sensing means, mechanism for comparing preselected sensings of the first-mentioned card-sensing means with preselected sensings of 35 said second card-sensing means including a slide device, and means controllable by said slide device for rendering said locking mechanism effective and ineffective.

35. The combination of card-sensing means and including a plurality of settable pins, mechanism 40 operable to lock said settable pins in set position during each machine cycle, a second card-sensing means, mechanism for comparing preselected sensings of the first-mentioned card-sensing means with preselected sensings of the 45 second-mentioned card-sensing means including a slide device, and means controllable by said slide device for rendering said locking mechanism ineffective when the compared sensings of both sensing means agree.

36. In a machine of the class described, the 50 combination of a plurality of sensing mechanisms, a respective card-feeding device for feeding cards to each of said sensing mechanisms, and a device automatically movable to respective 55 positions for rendering any of the feeding devices effective singly and settable to and retained in a position for rendering a plurality of feeding devices concomitantly effective.

37. The combination of two separate card-pickers for feeding cards; a pair of slides, each 60 slide associated with a separate card-picker, for operating said card-pickers; main operating mechanism for said machine including a main operating shaft, a cam on said main operating 65 shaft, intermediate means operable by said cam for actuating said slides; a pair of latches, movable to a plurality of positions and associated with said slides, for holding either slide inactive while the other is active; and means for positioning said latches to allow both of said slides to 70 act simultaneously.

38. The combination of two separate card-pickers for feeding cards; a pair of slides, each slide associated with a separate card-picker, for 75 operating said card-pickers; main operating

mechanism for said machine including a main operating shaft, a cam on said main operating shaft, intermediate means operable by said cam for actuating said slides; a pair of latches, movable to a plurality of positions and associated with said slides, for holding either slide inactive while the other is active; means for comparing the sensings of both of said card-sensing means, means controllable by the comparing means for automatically positioning said latches to hold first one then the other of said slides inactive, and means for positioning said latches to allow both of said slides to act simultaneously.

39. The combination of two card-sensing mechanisms, two mechanisms for feeding cards to said card-sensing mechanisms, means for comparing preselected sensings of both of said sensing mechanisms, a cam-shaft, a cam on said shaft for preventing operation of one of said card feeding mechanisms and allowing the other card feeding mechanism to operate, and means under control of said comparing means for operating said cam-shaft.

40. The combination of two card-sensing mechanisms; two automatically operable card stops, one for each of said sensing mechanisms; means for comparing preselected sensings of both of said sensing mechanisms, a cam-shaft, a cam on said shaft for preventing operation of one of said card stops, and means under control of a said comparing means for operating said cam-shaft.

41. The combination of two card-sensing mechanisms; two automatically operable card stops, one for each sensing mechanism; means 3 for comparing preselected sensings of both of said sensing mechanisms, a cam-shaft, a cam on said shaft for causing one of said card stops to hold a card for a number of machine cycles, and means under control of said comparing 4 means for operating said cam-shaft.

42. In a machine of the class described, the combination of two separate card-sensing mechanisms each including a stationary pin box, a set of pins associated with and movable by one of said sensing mechanisms, a separate set of pins associated with and movable by the other of said sensing mechanisms, and a device whereby a full movement of any of the pins of either of said sets of pins will cause a lesser movement 5 of a corresponding pin in the other of said sets of pins.

43. In a machine of the class described, the combination of two separate card-sensing mechanisms, a set of pins associated with and movable 5 by one of said sensing mechanisms, a separate set of pins associated with and movable by the other of said sensing mechanisms, a device for controlling machine operations, means for actuating said device, a slide operable by any of the 6 pins of said sets of pins for controlling the operation of said actuating means, and means for enabling and disabling said slide at the will of the operator.

44. In a machine of the class described, the 6 combination of two separate card-sensing mechanisms each including a stationary pin-box, a set of pins associated with and movable by one of said sensing mechanisms, a separate set of pins associated with and movable by the other of said 7 sensing mechanisms, and a plurality of levers whereby a full movement of any of the pins of either of said sets of pins will cause a lesser movement of a corresponding pin in the other of said sets of pins.

45. The combination of means for feeding a series of cards which are pre-punched with designation punchings and other punchings, means for feeding a second series of cards which are pre-punched with designation punchings, means for comparing the designation punchings of the cards in the first series with the designation punchings of the cards in the second series, and means under control of the comparing means 10 for transferring said other-than-designation punchings from each card in the first series to one or more cards of like designation in the second series.

46. In a machine of the class described, the combination of card-sensing means, a device for retaining a reading of said sensing means for a number of machine cycles, a second and separate card sensing means, means for comparing certain punchings sensed by said second card-sensing means with readings set up in said reading-retaining device, and means acting on a lack 20 of correspondence, of said punchings and readings, to clear the readings from said retaining device.

47. The combination of card-sensing means, a device for retaining a reading of said card sensing means for a number of machine cycles, card punching mechanism, and intermediate means for setting said card punching mechanism ac-

cording to the reading in said reading-retaining device.

48. The combination of two sets of movable pins, pin actuating means for moving the pins in one of said sets of pins, separate pin-actuating means for moving the pins of the second set, a slide device capable of movement in opposite directions, and means for transmitting motion from any pin in one of said sets to a corresponding pin in the other of said sets whereby when any pin 10 of either set is moved by its pin-actuating means and the corresponding pin is not moved by its pin-actuating means, said corresponding pin blocks movement of said slide device in one direction. 15

49. The combination of two sets of movable pins, pin actuating means for moving the pins in one of said sets of pins, separate pin-actuating means for moving the pins of the second set, a slide device capable of movement in opposite 20 directions, and means for transmitting motion from any pin in one of said sets to a corresponding pin in the other of said sets whereby when any pin of either set is moved by its pin-actuating means and the corresponding pin is also moved 25 by its pin-actuating means, said slide device is momentarily actuated, in one direction and immediately freed for movement in both directions.

KARL J. BRAUN.

Certificate of Correction

Patent No. 2,211,093

August 13, 1940

KARL J. BRAUN

It is hereby certified that error appears in the printed specification of the above numbered patent requiring correction as follows:

Page 2, first column, line 14, for the word "blank" read *detail*; page 8, first column, line 49, for "first" read *second*;

and that the said Letters Patent should be read as corrected above, so that the same may conform to the record of the case in the Patent Office.

Signed and sealed this 7th day of November, A. D. 1950.

[SEAL]

THOMAS F. MURPHY,
Assistant Commissioner of Patents.
